US0D1071368S

(12) **United States Design Patent** (10) Patent No.: **US D1,071,368 S**
(45) Date of Patent: ** Apr. 15, 2025

(54) **SAFETY RESTRAINT CLIP**

(71) Applicant: **Ronald Gigliotti**, Ashland, MA (US)

(72) Inventor: **Ronald Gigliotti**, Ashland, MA (US)

(**) Term: **15 Years**

(21) Appl. No.: **29/844,976**

(22) Filed: **Jul. 2, 2022**

Related U.S. Application Data

(63) Continuation-in-part of application No. 17/827,634, filed on May 27, 2022.

(51) **LOC (15) Cl.** **29-02**

(52) **U.S. Cl.**
